UNITED STATES PATENT OFFICE

108,964

DESIGN FOR A TUMBLER

Earl Gilson Redman, Huntington Park, Calif.

Application September 11, 1936, Serial No. 64,814

Term of patent 14 years

To all whom it may concern:

Be it known that I, Earl Gilson Redman, a citizen of the United States, residing at Huntington Park, in the county of Los Angeles and State of California, have invented a new, original, and ornamental Design for a Tumbler, of which the following is a specification, reference being had to the accompanying drawing, forming part thereof.

The figure is a perspective view of the article showing my new design.

The characteristic feature of my design resides in the arrangement of card pip characters of varying sizes about the outer periphery of the tumbler in the manner shown, said card pip characters being of a color contrasting with that of the tumbler. The heart shaped character shown is merely illustrative.

I claim:

The ornamental design for a tumbler, as shown and described.

EARL GILSON REDMAN.
